UNITED STATES PATENT OFFICE

HENRY W. TUTTLE, OF CHICAGO, ILLINOIS

MACHINE FOR EXPRESSING FRUIT JUICES AND THE LIKE

Application filed September 2, 1927. Serial No. 217,248.

The invention relates to a machine for expressing the juices from fruits such as oranges and analogous products, and for compressing plastic materials to a predetermined degree or condition, the primary object of the invention being to generally improve the construction and mode of operation, and thereby the efficiency and life of a machine of this character.

More specifically the improvements I have provided relate to the construction of the receiving hopper, to the feed screw and co-operating parts of the casing and the compressing and discharging devices whereby the same are rendered more efficient and more accessible and therefore more easily cleaned than heretofore in machines of this type. The improvements comprising my invention as applied to the screw form of press provide a continuous action device which, when used in treating fruits as oranges and the like, operates efficiently in compressing the pulp of the fruit and thereby separating in a highly efficient manner the juices or liquids therefrom. The invention is likewise adapted to the treatment of a wide range of plastic or semi-plastic materials which may by such treatment be reduced in bulk and compressed in being discharged from my improved device under predetermined conditions of pressure, thus insuring that the material on being discharged from the machine has been submitted to a uniform and predetermined degree of pressure. In short, the machine is adapted to the treatment of all plastic or semi-plastic materials where it may be desired to separate air or liquids therefrom.

Another object of the invention is to improve the construction of the liquid mixing and delivery trough and strainer in a machine of this character.

My improved machine is shown as operated by an electric motor and it is a further object of the invention to generally improve the construction of the gearing for driving the screw from the motor.

Other objects will appear from the following description, reference being had to the drawings showing the preferred embod-

iment of my invention, the novel features being set forth in the appended claims.

In the said drawings,

Fig. 1 is a longitudinal sectional view of the machine, the compressing screw being shown in elevation.

Fig. 2 is a diagrammatic view illustrating in detail the special construction of the compressing screw or worm and the co-operating portions of the casing, both of which are important features of my invention.

Fig. 3 is an elevation taken at the pulp discharge end of the machine.

Fig. 4 is a transverse sectional view through the pulp screw and casing.

Fig. 5 is an enlarged longitudinal sectional view of the parts at the discharge end of the machine as shown in Fig. 1.

Figs. 6 and 7 are fragmentary views showing details of parts at the discharge end of the machine, Fig. 6 being a section on line 6-6 of Fig. 8.

Fig. 8 is an end elevation view of the discharge mechanism taken at the left hand end as it appears in Fig. 5.

The reference character A designates generally the casing containing screw B which as is usual in this class of machines is mounted to rotate within the casing, being supported at the discharge end by trunnion C in bearing D which is a part of a specially constructed composite discharge device or nozzle consisting of the parts D and P through which the material after having been compressed is discharged.

The reference character E designates an electric motor or other suitable source of power mounted on base F which is preferably adjustably connected with casing G which serves as a support for the entire machine. Power is imparted to the screw B through gear pinion H on the motor drive shaft to the gears J and K which are connected to rotate with shaft L, and gear K is in mesh with the larger gear M connected with and by which the screw B is rotated, the relative sizes of the gears being such as shown in order to decrease the screw speed of the driving motor when, as in this em-

bodiment, the electric motor is employed as the source of power.

In machines of this character the life of the machine is determined by the alignment 5 of the screw in relation to its casing and this is limited to the life or durability of the bearings, and this is particularly true of the machine of my invention since the screw bearings at each end of the screw are 10 of ample proportions and completely center and sustain the screw so that the spiral ribs of the screw do not at any time in the operation of the screw contact with the spiral ribs of the casing, there being preferably 15 a clearance between these parts sufficient to prevent contact between the ribs of the screw and those of the casing, such clearance being only ordinarily sufficient to insure that the outer spiral periphery of the 20 screw does not at any time contact with the surrounding casing.

To maintain proper alignment and maximum durability I have provided three annular bearings for the screw and one special 25 anti-friction thrust bearing, all of which are readily renewable by the user without the services of an expert mechanic. The screw B is provided at its driving end with a shaft 10 journalled to rotate in the main 30 supporting bearing 11 which is preferably provided with a renewable bronze or analogous bushing 12, the bearing 11 being preferably an integral part of casing G. The aforesaid gear M is keyed or otherwise attached 35 to shaft 10 and to further support the screw and its shaft 10 I provide an auxiliary bearing 13 with a bushing 14. To take the end thrust of the screw I provide an anti-friction bearing of the ball or roller type 40 which is shown specifically as consisting of the hardened steel rings or perforated plates 15, 16 interposed between the gear M and the bearing 13 around shaft 10 and having an anti-friction ball or roller bearing cage 45 interposed therebetween as indicated at 17. At the discharge end of the screw the aforesaid trunnion C thereon is journalled in said bearing D which is preferably constructed as a part of the supporting member 19 for 50 the discharge valve stem 20, the valve seat 21 being formed around a discharge orifice in the discharge casing P, the latter being detachably connected with the screw threaded discharge end of the main screw 55 casing A as indicated at 18 in Figs. 1 and 5. The valve stem 20 may be rigidly supported as shown by screw threading into its support 19 and it carries the valve 22 which is slidably mounted on the stem. The function 60 of the valve 22 is to control the pulp discharge so that a predetermined pressure may be exerted thereon and the construction and mode of operation of my improved valve construction and co-operating parts 65 enables me to attain results not heretofore

attained in machines of this character. By offering a predetermined resistance which may be adjusted as desired, my improved discharge valve construction enables the machine to extract with uniformity to any predetermined and desired extent the liquids, and compress the solids to any predetermined degree of pressure regardless of the rate of feed in relation to machine speed, which has not been possible with prior devices of this character.

The valve 22 is preferably circular in form and co-operates with its seat 21 as shown in Fig. 5 to completely close the discharge orifice. It is urged toward its seat 21 and a stop on the outer end of support 19 by a compression spring 23 surrounding the stem 20 and restrained by the adjustable nut 24 screw threaded on the stem 20.

In a compressing and juice extracting machine the efficiency will depend upon the degree of pressure and the uniformity of pressure applied to the material being treated. The discharge orifices of machines of the prior art have been controlled by various adjustable devices that merely change the cross sectional area of the discharge opening and consequently irregularities in speed and feed result in widely varying degrees of pressure and faulty and wasteful operation.

With my improved spring valve controlled discharge orifice a uniform degree of pressure will at all times be exerted on material being treated regardless of its character or the rate of feed, dependent solely upon the degree of adjustment predetermined by the operator in tensioning compression spring 23 by adjusting nut 24. The peripheral ring or part 19 supports this valve stem 105 supporting member by a close sliding fit in an enlarged portion of the casing P, fastening on the main screw casing, the two parts of the support 19 being connected by opposite radial bridges or spokes 25 (Figs. 1, 5, 6 and 8) which are preferably bevelled at their forward edges as at 26 to present cutting edges to outflowing material as it leaves the screw on its passage to the discharge valve orifice.

In machines of this character there is a tendency to scatter and extrude material at the discharge end which is sometimes sought to be avoided by the use of cloth shields and other unsanitary devices. I provide around the discharge casing and orifice therein a pipe 30 of cylindrical or other desired form which is detachably connected to the discharge end of casing P by suitable means as bayonet joints 31 (Fig. 7) co-operating with pins 32.

The screw casing, the screw, the feed hopper, the juice screen and the juice collecting trough all contain improved and valuable features of my invention.

The screw B is constructed as in the usual practice in the form of a frustum of a cone with the large end at the receiving or hopper end of the screw casing A. In Fig. 1 it will be seen the pitch of the screw gradually diminishes toward the discharge end for about two thirds of its length after which the pitch of the same is constant. The shape of the convolutions of the ribs and grooves of the screw as well as the shape of the co-operating convolutions of grooves and ribs on the interior of the screw casing are a departure from prior art practices. This is best illustrated by reference to Fig. 2 in which the shapes of these respective ribs and grooves are diagrammatically shown. I find it desirable to decrease the difference in the relative diameters of the respective ends of the screw so that the diameter of the same at the discharge end is more nearly that of the intake or hopper end than usual in the art as shown in the drawings. This gives greater space for the passage of material and tends to avoid grinding action thereon and also affords a longer path of travel and greater squeezing efficiency. I also find it desirable to form the spiral grooves in both the casing and in the screw of ample proportions much wider and deeper in cross section than heretofore in this art. I also have discovered that I am able to greatly increase the efficiency of the screw and its co-operating casing in their squeezing action by forming the spiral grooves in the casing of the same pitch as the screw and consequently of the same width as the grooves of the screw and approximating more nearly than in the prior art the area in cross section of the grooves in the screw. The spiral grooves of the casing will be formed opposite to the corresponding spiral grooves of the screw, i. e. one right hand spiral and the other left, and the effect of this construction is for the screw to carry material in the spiral path of the casing. This feature of construction enables me to improve the effect of the action of the screw upon the material being treated as the material is fed forwardly around the spiral groove of the casing and is caused repeatedly to be forced over a juice screen or strainer 40 that is positioned longitudinally of the casing at the bottom thereof. The top side of the strainer is positioned in the casing in the plane of the inner edges of the spiral ribs and in approximately the plane of the periphery of the ribs on the screw. It is also curved on its upper side to fit the curvature of the screw. At each side of the opening for the strainer 40 the material of the casing is thickened or formed upwardly as indicated at 52 so as to fill the grooves to the level of the tops of the spiral ribs of the casing, this filling being wedge shaped. The effect will be to cause the material as it is carried around the spiral grooves of the casing by the screw to be subjected each revolution of the screw to a squeezing action as it is forced through the restricted passageway between the lower side of the casing and adjacent strainer plate by the screw. However, since the spiral grooves of the screw and of the casing are of progressively decreasing area in cross section, it will be seen that the restricted passageway at the strainer plate 41, while it has the effect of rather suddenly or abruptly decreasing the available area in cross section of the material being fed forwardly by the screw, the effect of this rather sudden contraction at the strainer is not to permit any substantial release of the material or sudden expansion of the same as it passes over the strainer plate, because by that time the forward rotation and travel of the screw will have contracted the cross sectional area of the screw channel a substantial amount so that the material after passing over the strainer on each rotation will be positively fed forwardly and gradually compressed by the engagement between the ribs of the screw and the casing, and the action is again repeated as the material is advanced and passes over the strainer at each complete revolution of the screw. In other words, when the screw is in operation and the machine filled to capacity with material being operated upon, the stream of the material from the hopper to the discharge orifice of the casing will be of gradually and uniformly decreasing area in cross section, and the effect or choking action of the strainer will be to somewhat abruptly diminish the area of the stream of material in cross section as it passes over the strainer, but the release due to the shape of the casing is substantially only equal to the amount of the normal contraction of the available space between the grooves in the screw and the casing so that immediately after passing over the strainer for a short distance, the cross sectional area of the stream will be substantially constant, after which there will continue to be, during the remainder of the revolution of the stream of the material until it again passes over the strainer, a progressively decreasing area.

Another feature of construction of the screw and its co-operating casing resides in my discovery that by shaping the respective grooves in cross section of both the screw and the casing, as shown in Figs. 1 and 2, I very materially increase the effectiveness of the conveying and squeezing action of these parts. In Fig. 2 this feature is shown by the shape of the walls of the respective grooves indicated by the arrows. I form the rear walls of the grooves in the screw approximately parallel with the angle of the pitch of the screw. This af-

fords a superior contact of the screw with material being acted upon and the effect is improved by increasing the angle of the opposite wall of the corresponding groove 5 in the casing in relation to the axis of the screw. The result is to bring these respective co-operating walls of the screw and casing grooves as indicated at α and γ respectively, (Figs. 1 and 2) into approximate 10 parallelism as illustrated diagrammatically in Fig. 2, which greatly increases the conveying and squeezing action of these elements on soft pulpy or plastic materials, as 15 the cross sectional area of the spiral co-operating grooves of the casing and screw progressively decrease during the progress of the material through the machine.

The action of the screw and casing with 20 their non-grinding, co-operating spiral ribs and grooves is to form the material in the casing to the shape of an internally and externally threaded nut, which as the screw rotates is smoothly carried forward in a circular direction, progressively diminishing 25 in bulk and increasingly being compressed, and as the discharge opening of the casing is completely closed by a valve, which may be regulated to oppose any resistance desired, the nut-shaped material 30 will be compressed to the predetermined pressure required to eject it.

The aforesaid constricted portions in the spiral grooves of the casing adjacent the juice trough and strainer may be understood 35 by reference to Figs. 1 and 4. In Fig. 4 the screw B is shown in section and the groove wall appears in elevation as indicated at 50. The wall γ of the casing groove also appears in this view as indicated, and the casing groove is seen to be 40 filled near the bottom of each convolution thereof as indicated at 52 at each side of the juice strainer 40 to the top of the strainer and to the top of the threads or spiral 45 ridges between the grooves of the casing so that at the bottom the spiral threads of the screw will travel in the approximate plane of the outer periphery of the screw threads of screw B. This results in a distinct compression 50 of the material passing through the machine at each passage of the material over the juice strainer greatly accelerating the compression and juice extracting action whereby my machine is found to extract 55 and conserve a much greater percentage of fruit juices than in any machine heretofore produced without mingling solids or undesirable particles with the juice. Extensive tests that I have made show that this will 60 result in a saving of juice amounting to approximately four quarts to six quarts of juice in a case of oranges and other fruits and materials in like proportion. This improved squeezing action with the named results 65 is made possible by the co-operation of

the improved screw mechanism described, including the position of the juice strainer and the described approximately parallel screw surfaces α and γ in combination with my improved discharge spring controlled valve mechanism which, as stated, renders the pressure constant, regardless of variations in speed of the screw, character of materials being operated upon or variations in feed relative to machine speeds, all of 70 which conditions have proven troublesome in analogous machines of the prior art.

It will be noted that the restriction of the cross section of the grooves adjacent the strainer in the casing does not prevent the material therein from progressively and smoothly passing forward nor is there an expanding action after passing over the strainer as the area of the grooves in the screw and casing walls are of progressively 80 diminishing area, the area of the grooves on the after side of the strainer being of progressively less area than the area over the strainer. This prevents alternate compressing and expanding action and causes 85 the material therein to progressively diminish in bulk.

The juice strainer 40 extends longitudinally of the bottom of the casing, closing, except for the perforations 41 therein, the juice slot 55 that extends lengthwise of the casing from a point below the hopper to near the end of the screw, as shown in Fig. 1. It is supported by integral bridge pieces 56, 57 of casing A, spaced across the juice 95 slot and by ledges 58, 59 at the ends thereof.

Attached to the casing as a continuation of juice slot 55 is a collecting and mixing trough 70 connected by stirrups 71, 72, which are pivotally mounted at 74 in the casing 100 walls as shown and are capable of being used to detachably clamp the trough 70 to the casing so that it may be quickly and easily removable for cleaning. Spring 105 pressed plungers or locking pins 73 are used to secure the stirrups in locking position by engaging shallow notches in the ends of the trough, and these notches are so formed that by a slight blow or pressure on the free end of the stirrups they may be quickly caused to engage or disengage the trough. The trough 70 is in the form of an elongated funnel depressed preferably at the outer or discharge end of the casing and provided 110 with a downwardly opening discharge nozzle 75.

I prefer to make the casing A and parts attached thereto and supported thereby readily removable for cleaning purposes. At the hopper end of the casing A it is 115 adapted to telescope over a peripheral shoulder on the frame G as indicated at 80 (Fig. 1). A quick detachable connection is provided by the locking stirrups 82 pivotally connected to casing frame G and pro- 120

vided with screws 83 adapted to engage projecting lugs 84 on the casing A.

The hopper 95 is preferably rectangular in horizontal cross section as shown.

5 5. A special feature of improvement of my invention resides in the detachable hopper 100 of conical form attached to plate 101, which serves as a detachable baffle or partial cover to hopper 95 and serves to trap materials and prevent splashing of juices or backward movement of materials from the feed screw and its casing during the operation of the screw on material passing through the machine.

10 15. From the foregoing description it will be seen my improved machine is intended to separate the liquid and solid content of plastic materials, so that either or both may be recovered in their separate state and for 20 compressing plastic material to a predetermined condition and pressure.

What I claim as my invention and desire to secure by Letters Patent is:

1. In combination, a screw casing provided on the interior thereof with spiral inwardly projecting ribs having feed grooves therebetween, and a co-operating screw revolvably mounted within said casing and being provided with a continuous spiral rib 25 extending from end to end thereof, and having a continuous spiral feed groove between said ribs and co-operating with the spiral feed grooves of the said casing, there being a portion of the side wall of each convolution of the said groove in the casing formed to lie approximately parallel to the plane of the pitch of the screw, one of the side walls of the grooves of the said screw opposite the aforesaid wall in the groove of 30 the casing being formed also approximately parallel to the plane of the pitch of the screw and consequently approximately parallel with the opposing wall in the corresponding groove of the casing.

45 2. In combination, a screw casing in the approximate form of a frustum of a cone, having a hollow interior in the approximate form of the frustum of a cone, the interior thereof from end to end being formed 50 of ribs in spiral formation with spiral grooves lying between said ribs, and a screw co-operating with the interior of said casing being of the approximate form of the frustum of a cone, and having spiral ribs 55 formed thereon with spiral grooves between said ribs for co-operating with the aforesaid spiral grooves in the casing, the wall of each of the said grooves in the casing adjacent the discharge end of the screw being formed 60 to lie approximately parallel with the plane of the pitch of the screw and the wall of each of the said spiral grooves in the screw opposing the last said walls in the grooves of the casing being formed to lie approximately 65 in the plane of the pitch of the screw

and consequently approximately parallel to the aforesaid portion of the wall of the groove in the casing, a discharge device for permitting the passage of liquids from the bottom of the casing and below the screw, 70 and means in the casing adjacent the said discharge device for constricting the grooves in the casing adjacent the said discharge device.

75 3. In combination, a screw casing, a screw revolvably mounted therein, the said screw casing being provided from end to end thereof with internally projecting ribs in spiral form with co-operating grooves between the said ribs in the casing, the walls of the said grooves in the casing at the side thereof toward the discharge end of the casing being formed to lie for a portion of their length approximately parallel to the plane of the pitch of the screw, and the co-operating wall in each groove of the screw being also formed to lie approximately in the plane of the pitch of the screw and parallel to the aforesaid portion of the wall 80 of the groove in the casing.

85 4. In combination, a screw casing having on the interior thereof inwardly projecting ribs in spiral formation, a screw for co-operating with the interior of said casing and being provided with ribs in spiral formation to co-operate with the ribs in the casing, the major portions of the diametrically opposite or opposing walls of the grooves in the screw and casing being approximately parallel with each other, a juice discharge device in the casing adjacent the screw along the lower side thereof, the said co-operating grooves in the screw and casing being for a portion of the length of the screw and the casing of gradually decreasing area in cross section from the receiving end to the discharge end of the screw and casing, and means for constricting the total area of the grooves in cross section formed between the co-operating ribs in the casing and the screw 90 adjacent the juice discharge device in the casing.

95 5. In combination, a screw casing, a screw revolvably mounted therein, the said casing being formed with spiral inwardly projecting ribs with corresponding grooves therebetween, a screw revolvably mounted within the casing and co-operating with the said spiral ribs and grooves therein, the said screw being provided with ribs in spiral formation with spiral grooves lying therebetween, the walls of each convolution of the grooves toward the discharge end of the casing being cut out to lie approximately 100 parallel to the plane of the pitch of the screw, and the wall of each convolution of the groove of the screw at the side thereof toward the receiving end of the casing being cut to lie in the approximate plane of 105 the pitch of the screw and consequently 110 ap-

proximately parallel with the aforesaid wall in the groove of the casing, and means for rotating the screw within the casing.

6. In combination, a screw casing, a screw 5 revolvably mounted therein, there being co-operating grooves in the casing and the screw whereby to feed material from one end to the other of said screw and casing, the discharge end of the casing being screw threaded, and a discharge device detachably connected with the screw threaded portion of the said casing, the said discharge device comprising a discharge nozzle with a constricted opening in the outer end thereof, 15 a valve mounted to reciprocate in said constricted opening, a spider comprising a bearing for the outer end of the screw, there being discharge passages around said bearing leading to the said constricted discharge 20 opening and valve; a shaft connected with said spider portion adapted to support the said valve, and spring means on the shaft for controlling the movements of the valve.

7. In combination with a screw and casing 25 therefor, a discharge device detachably connected with the casing at the delivery end thereof comprising a nozzle with a restricted opening, a spring controlled valve for controlling the said opening, a bearing for 30 supporting the discharge end of the screw, said bearing being supported by the said discharge device and forming a part thereof, and a shaft supported by said bearing for guiding the movements of the said spring 35 controlled valve.

8. In combination with a screw and casing therefor, a discharge device detachably connected with the casing at the delivery end thereof comprising a nozzle with a restricted 40 opening, a spring controlled valve for controlling the said opening, a bearing for supporting the discharge end of the screw, said bearing being supported by the said discharge device and forming a part thereof, a shaft supported by said bearing for 45 guiding the movements of the said spring controlled valve, and means for adjustably controlling the normal spring pressure on said valve.

50 9. In combination, a screw casing, a screw revolvably mounted therein, a discharge device detachably connected with the delivery end of the said screw and being provided with a restricted discharge opening, a 55 spring controlled valve for the said opening, and a discharge spout detachably telescoped over the discharge end of the said casing around the said spring controlled valve opening.

60 10. In combination, a screw casing, a screw revolvably mounted therein, a discharge device detachably connected to the casing at the discharge end thereof and provided with a restricted discharge spring valve controlled opening, a spider carried within the

discharge opening of said device and comprising a bearing for the free end of the screw together with a radially extending arm for centering the said bearing, the edge of the said arm adjacent the screw being provided with a cutting edge to prevent the lodgement of material being discharged by the screw through said device.

65 11. In combination, a screw casing, a screw rotatably mounted therein, there being a longitudinal juice discharge slot at the bottom of the casing, a juice strainer detachably mounted in said slot, a juice trough adapted for detachable connection with the screw casing adjacent the said longitudinal discharge opening therein and communicating therewith, comprising a hopper with a depressed portion adjacent the outer end thereof, a discharge spout connected with the depressed outer and lower end of the juice trough, and means for quick detachable connection of the juice trough with the casing comprising locking stirrups pivotally connected with the casing and adapted to operate with the ends of the said juice spout.

70 12. In combination a screw having spiral ribs and spiral grooves between said ribs, said spiral grooves being of constantly diminishing pitch and cross sectional area from one end to the other end of the said screw, a screw casing provided with spiral ribs and having grooves between said ribs, said ribs and grooves on said casing traversing a path in opposite direction to the direction of the path of the ribs and grooves of the screw but lying adjacent to and co-operating with the said ribs and grooves in the screw, the grooves in the casing being of constantly diminishing cross sectional area 75 from the intake to the discharge ends thereof, the grooves of greatest area in both the screw and the casing being both adjacent the intake end of the casing and the grooves of least area of both screw and casing being at the discharge end thereof, the said screw being revolvably mounted within the casing, and means for actuating the screw within the casing in order that the material entering the casing may be compressed and formed into a core having substantially the form of an internally and externally threaded nut, the inside of which will conform to the spiral of the screw and the outside of which will conform to the spiral of the casing within which said core, as the screw is revolved, will travel forwardly in a spiral direction following the spiral grooves in the casing and progressively become of less cross sectional area from the intake to the discharge end of the casing.

80 13. In combination with a screw and casing therefor, a discharge device on the casing at the delivery end thereof comprising a nozzle with a restricted opening, a spring controlled valve for normally closing said

opening and adapted to be forced out of said opening by the pressure of material on the inside of said casing for discharging material being operated on by said screw 5 within the casing, a bearing at the discharge end of the casing for supporting the discharge end of the said screw, and a shaft concentric with the axis of said bearing and supported by the material of said bearing 10 for guiding the movements of the said spring controlled valve.

14. In combination, a screw casing, a screw rotatably mounted therein, there being a longitudinal juice discharge slot in the bottom of the casing, a juice strainer detachably mounted to communicate with said slot, a juice trough adapted for detachable connection with the screw casing adjacent the said longitudinal discharge opening therein 20 and communicating therewith, a discharge spout having a venting function for the said juice trough, and a spring actuated quick detachable locking device for connecting and disconnecting the juice trough in relation to 25 said slotted screw casing.

15. In combination with a screw and casing therefor, a discharge device carried by the delivery end of the casing and comprising a nozzle with a restricted opening, a valve adapted normally to close the said opening, an adjustable spring for holding the said valve normally in a closed position, and a non-rotatable shaft supported by the 30 casing on the approximate radial center of the said opening guiding the movements of the said spring-controlled valve in relation to the said restricted discharge opening.

16. In a machine of the described character, the combination with a rotatable screw 40 and a casing therefor, of a discharge device at one end of the casing comprising a nozzle having a restricted opening providing a valve seat, a spring-controlled valve for cooperating with said restricted valve seat 45 opening, and means for guiding the movements of said spring-controlled valve in relation to the said restricted valve opening comprising a non-rotatable guide shaft supported by and positioned at the outer extremity of the casing beyond the said restricted discharge valve opening, and a coiled spring, one end of which engages the 50 said valve and the other end of which is adjustably secured in relation to said guide shaft whereby to vary the resilient pressure of said spring on said valve.

In testimony whereof I have signed my name to this specification on this 11th day of August A. D. 1927.

60 HENRY W. TUTTLE.
